[57] CLAIM

The ornamental design for a toy projectile launcher, as shown and described.

DESCRIPTION

FIG. 1 is a perspective view of a toy projectile launcher embodying my new design;
FIG. 2 is a right side elevational view thereof;
FIG. 3 is a left side elevational view thereof;
FIG. 4 is a top plan view thereof;
FIG. 5 is a bottom plan view thereof;
FIG. 6 is a front elevational view thereof;
FIG. 7 is a rear elevational view thereof;
FIG. 8 is a perspective view thereof in a collapsed position; and,
FIG. 9 is a perspective view thereof in a cocked and loaded position.

Broken lines showing a projectile are for illustrative purposes only and form no part of the claim.
